ISAAC V. HOLMES, OF NEW YORK, N. Y.

Letters Patent No. 88,294, dated March 30, 1869.

IMPROVED METALLIC STUDDING FOR FIRE-PROOF WALLS.

The Schedule referred to in these Letters Patent and making part of the same.

To all whom it may concern:

Be it known that I, ISAAC V. HOLMES, of the city, county, and State of New York, have invented a new and improved Mode of Constructing the Metallic Studding used for Supports to Lath in the Formation of Fire-Proof Walls; and I do hereby declare that the following is a full and exact description thereof, reference being had to the accompanying drawing, and to the letters marked thereon, making part of this specification, in which—

Figure 1 is a perspective view of the studs and adjustable lugs in position, with laths attached.

Figure 2 is a perspective view, showing the arrangement of the adjustable lugs with the end of stud.

Figures 3, 4, 5, 6, 7, and 8, show different sections of studs.

Figures 9 and 10 show sections suitable for using very thin metal, and for lathing that does not require the edges to be slitted.

At present it is customary to use, for the studding, to support the sheets or strips forming the lath-surface, flat bands or bars of metal, of suitable width, and varying from one-fourth to three-eighths of an inch in thickness, according to the height of ceiling, and fastened at each end, by either turning flanges on the end of stud, or by riveting on angle-pieces. This thickness is necessary to give stiffness, on account of the elasticity of such long strips of metal, they being ordinarily from ten to eighteen feet long.

Then, by being confined to a positive length by the turned flanges, or fixed ends, there is much trouble and expense in fitting them to the varying heights that buildings require, it being found that some will be a little too long, while others will be as much too short, necessitating a loss of time and labor in fitting them in place.

The object of my invention is to obviate both of these objections, that is, to save the weight of material, and provide for the varying lengths.

To enable others skilled in the art to make and use my invention, I will proceed to describe the construction and use.

In the formation of the stud, I use thin sheet-metal, say about one-sixteenth of an inch thick, and of such width as may be necessary, and then, by any suitable means, corrugate or bend it, the ridges or corrugations running lengthwise of the strip.

It will at once be seen that I have given to the thin strip of metal a very stiff form, and that, by varying the depth and number of these corrugations, I can increase that stiffness very much, with a very slight increase of weight; and that I will then have a stud weighing about one-fourth as much as those now used, equal or superior in stiffness, and at about one-third

the cost, as such corrugated bands or strips will be furnished by the rolling-mills.

The form, or shape of these bends or corrugations may be varied to suit the manufacturer's idea of which is the best. Several of them are shown in figs. 3, 4, 5, 6, 7, and 8, but I do not confine my invention to any particular form or curve. Figs. 9 and 10 represent forms where a very thin sheet-metal can be used, and is suitable as a support for sheet-lathing.

In the construction of the adjustable lugs, or supports for studs, (an enlarged view of which is represented at fig. 2)—

A is the end of the stud, in which are punched the oblong holes c c.

B B are the lugs, with the foot turned for fastening to floor or ceiling.

c c are circular holes, punched through body of lug, to correspond with the holes c c in end of stud.

d d are ordinary head-bolts, passing through the stud and lug, and, when screwed up securely, hold the two together.

I wish it understood that I do not confine myself to the use of an adjustable lug, in combination with a corrugated stud, as it can be applied to the ordinary plain stud with equal advantage; also, the adjustable feature of play in the openings of lug and stud may be obtained, by having the holes circular, and punched larger in diameter than the bolts, and so obtain the necessary movement.

The operation and advantage of using this combination, are, that the studs can be cut at the shops all of one length, suitable to the average height of ceiling required, have the holes c c punched and fitted with the lugs, then taken to the building, the lugs fastened to floor and ceiling, and the studs adjusted to the proper level, by means of the oblong holes, and the bolts screwed up, leaving the studs in position, thereby obviating all trouble, delay, and unnecessary expense by this adjustable feature.

Claims.

What I claim as my invention, and wish to secure by Letters Patent, is—

1. A stud formed of corrugated sheet-metal, for supporting a lath-surface, and constructed substantially as and for the purpose described.

2. An adjustable lug, in combination with a metal stud, used for supporting a lath-surface, constructed substantially as and for the purpose set forth.

ISAAC V. HOLMES.
